UNITED STATES PATENT OFFICE.

EDWARD B. VANDERGAW, OF BROOKLYN, AND JULES HEINRICH, OF NEW YORK, N. Y., ASSIGNORS TO FRED BUTTERFIELD & CO. INC., OF NEW YORK, N. Y., A CORPORA-TION OF NEW YORK.

DESIGN FOR FLOCKED VOILE FABRIC.

Application filed September 18, 1923. Serial No. 7,240. Term of patent 3½ years.

To all whom it may concern:

Be it known that we, EDWARD B. VANDER-GAW and JULES HEINRICH, citizens of the United States, residing, respectively, in the boroughs of Brooklyn and Manhattan,
in the city and State of New York,
have jointly invented a new, original,
and ornamental Design for Flocked Voile Fabric, of which the following is a specification, reference being had to the accompanying drawing, forming part hereof.

The figure is a plan view of a piece of flocked voile fabric showing our new design.

We claim:

The ornamental design for flocked voile fabric, as shown.

EDWARD B. VANDERGAW.
JULES HEINRICH.
